UNITED STATES PATENT OFFICE.

HOWARD BUTTRESS, OF LOS ANGELES, CALIFORNIA.

SASH-LOCK.

No. 905,984.

Specification of Letters Patent.

Patented Dec. 8, 1908.

Application filed February 6, 1908. Serial No. 414,622.

To all whom it may concern:

Be it known that I, HOWARD BUTTRESS, a citizen of the United States, residing at Los Angeles, in the county of Los Angeles and 5 State of California, have invented a new and useful Sash-Lock, of which the following is a specification.

This invention relates to a sash lock which will normally permit the sash to be freely 10 closed, but prevent its being opened further than it is already opened, and an object of the invention is to provide convenient and easily operated means for releasing the lock to enable the sash to be opened.

15 Another object of the invention is to provide a sash lock of this character with means for locking the operating means in set position such that the sash can be freely moved in either direction.

20 Another object of the invention is to provide a sash lock of this character with means for locking the operating means in set position in which the sash can be freely closed and not opened, thereby safeguarding the 25 operating means against operation from outside the window to release the sash.

In the accompanying drawings:—Figure 1 is an elevation of the lock, the sashes being removed. Fig. 2 is a vertical section 30 through the lock and adjacent part of the sash and casing. Fig. 3 is a horizontal section thereof. Fig. 4 is a perspective of the lock with the case removed. Fig. 5 is a perspective of the same.

35 The lock comprises a base plate 1, bolts 2 slidably mounted therein, springs 3 for moving the bolts to locking position, a yoke lever 4 for moving the bolts to unlocking position, a main lever 5 operating the yoke lever, and 40 a knob 6 for operating the main lever.

A yoke 7 connecting the two bolts is preferably arched, as shown, and the yoke lever 4 is slotted as at 8 to embrace one of the bolts 2 and extend under the arch of yoke 7. Said 45 yoke lever 4 is pivoted on standards 9 extending from base plate 1, and the main lever 5 is pivoted on standards 10 also extending from said base plate, said standards being preferably formed by slotting the base plate 50 and bending up the metal at the ends of the slots. A tubular guide 11 secured to base plate 1, by its flange 12, receives the knob 6 which slides in said guide and projects at its inner end to engage the main lever 5. The 55 knob 6 is provided with a projection or pin 13, which, in the sliding movement of the

knob 6, works in a longitudinal slot 14 in the tubular guide 11, said slot having notches or lateral extensions 15, 16 at the inner and outer ends thereof to receive the said pin or 60 projection. A case 17, formed as a channel plate, extends over or back of the above mentioned parts and is secured to base plate 1 as by means of lugs 18 on the side flanges of said case passing through slots 19 in the 65 base plate 1 and upset at their ends. Said case is provided with holes 20 fitting the bolts 2 to aid in guiding the same, the springs 3 for normally moving the bolts to locking position being arranged around the bolts and 70 between the said case and the yoke 7 connecting the bolts. Said yoke 7 projects through slots in the bolts so as to form an effective abutment for the spring, and said yoke also serves as a stop for limiting the 75 outward movement of the bolts.

The base 1 is formed with means for attachment to the window casing 21 at the sides thereof in such manner that the bolts 2 will project into the ways in which the 80 stiles of the sashes run. The end portions of the base plate extend under the molding or stop 22 at the inside of the window casing, the tubular guide 11 extending through a hole in said stop so that the knob 6 projects 85 from the said stop at the side of the window. Each window sash 25 is provided with a series of detent means comprising inclined tongues 23 in a longitudinal groove 24 in the edge of the sash stile, these detent means 90 being inclined oppositely on the two sashes, namely, upward and outward on the lower sash and downward and outward on the upper sash. The sash lock is so placed that the bolts 2 extend into the grooves 24 in the 95 sashes and engage the detent means 23 therein.

The operation of the device is as follows:—The normal condition of the device may be considered as that shown in Fig. 3, the pin of 100 knob 6 being directly at the outer end of slot 14. In this position the bolts are held in locking position by their springs 3, and if either of the sashes be in closed position it can not be opened, as the detent means 23 105 will engage with the corresponding bolt to prevent such movement. If either of the sashes be partly opened it can not be further opened for the same reason, but it can be closed, the inclined portions of the detents 23 110 engaging the bolt to press the same back and allow passage of the detents. The yoke

lever 4, and main lever 5 do not interfere with such motion, the bar 7 simply working back and forth without effecting yoke lever 4.

In the normal set position of the operating 5 knob 6, shown in Fig. 3, the sash can be released at any time for free opening thereof, by simply pressing on the knob 6, the projection 13 therein moving inwardly in the slot 14 in the tubular guide, the knob 6 in 10 this movement operating main lever 5 which in turn operates yoke lever 4 to press the yoke 7 back against the action of springs 3 and move the bolts to unlocking position, so that either or both sashes can be freely 15 opened as far as desired. On releasing the knob 6, the springs 3 move the bolts to locking position leaving the device in normal condition as before, so that the sash can not be further opened without access to the operating means 6, thus preventing opening of 20 the sash from outside the window. If it is desired to fully release the sashes so that they can be freely moved up or down without being unlocked each time, the knob 6 is 25 pushed in and turned so as to cause the projection 13 thereon to enter the notch or slot extension 15 at the inner end of slot 14, thereby holding the bolts in unlocking position. If, on the other hand, it is desired to 30 prevent operation of the operating knob 6, for example, by means of a person reaching under the opened window attempting to press in said knob, by use of a stick or otherwise, the said knob is turned while in its 35 outermost position so as to bring the projection 13 thereof into the notch or slot extension 16 at the outer end of slot 14. In this position the knob 6 can not be operated by simply pressing it in, but must first be turned 40 back into line with the slot 14, an operation which would be practically impossible for a person outside of the window, when the sash is only slightly open, as for ventilation.

What I claim is:—

- 45 1. A sash lock comprising two bolts, a yoke connecting the bolts, springs pressing the bolts to locking position, a yoke lever engaging said yoke to move the bolts to unlocking position, a main lever engaging the yoke lever, a slidably mounted knob engaging said main lever, means for locking said knob in position to hold the bolts in unlocked position, and means for locking said knob in position to allow the bolts to move 50 to locking position.
- 55 2. A sash lock comprising a pair of locking bolts, springs for moving the bolts to locking

position, a yoke connecting said bolts, a pivoted yoke lever engaging said yoke, a pivoted main lever for operating the yoke lever, 60 and a slidable knob for operating the main lever.

3. A sash lock comprising a pair of locking bolts, springs for moving the bolts to locking position, a yoke connecting said bolts, a pivoted yoke lever engaging said yoke, a pivoted main lever for operating the yoke lever, 65 and a slidable knob for operating the main lever, said yoke lever being slotted and one of said bolts passing through the slotted portion of the yoke lever.

4. A sash lock comprising a base plate, a case secured thereto, a pair of locking bolts slidably mounted in the base plate and case, a yoke extending into slots formed in the 75 said bolts, a coil spring encircling each bolt, one of said springs bearing against said case and said yoke, standards projecting from said base plate, a yoke lever pivoted to said standards and engaging said yoke, the other 80 coil spring bearing against said case and said yoke lever, a pivoted main lever engaging the yoke lever, and a slidable knob for operating the main lever.

5. A sash lock comprising a pair of bolts, a 85 yoke connecting said bolts, springs for pressing said bolts to locking position, a pivoted yoke lever engaging said yoke, a pivoted main lever engaging the yoke lever, a tubular guide open at both ends, a knob slidably 90 and rotatably supported in said tubular guide, one end of said knob abutting against the main lever, said tubular guide having a longitudinal slot with offset slots at each end of the longitudinal slot, and a pin on said 95 knob adapted to slide in said slots.

6. A sash lock comprising a pair of locking bolts, an arched yoke with its ends extending through slots formed in said bolts, spring means for normally holding said bolts in 100 locking position, a curved pivoted yoke lever slotted to receive one of said bolts and adjacent portion of the yoke and engaging with the arched portion of the yoke, a pivoted main lever, a slidable knob for operating the 105 main lever, and means for locking said knob when in depressed or retracted position.

In testimony whereof, I have hereunto set my hand at Los Angeles, California, this 30th day of January 1908.

HOWARD BUTTRESS.

In presence of—

GEORGE T. HACKLEY,
FRANK L. A. GRAHAM.
